BALLAST REMOVER

Royce Kershaw, Montgomery, Ala.

Application June 12, 1946, Serial No. 676,136

4 Claims. (Cl. 37—104)

1

This invention is a ballast remover for use in reconstruction of railway track bed, the primary object of which is to provide means of comparatively simple construction and operation for quickly and with little effort removing the ballast from between cross ties preparatory to the removal and replacement of ties.

A further object of the invention is to provide a tie bed cleaner or ballast remover which is capable of being easily and quickly applied to or removed from the trackway, which embodies a power unit for carrying out the ballast removing operation, which is featured by feed and adjusting mechanism for determining the depth of removal of ballast as well as to determine the length of movement of the ballast clearing mechanism.

A further object of the invention is to provide a tie bed cleaner or ballast remover involving a unit supported by a carrier to run upon the trackway, and involving mechanism capable of being moved from side to side of the track in order that the ballast may be cleared from the center to both sides of the track.

With the foregoing objects in view, together with others which will appear as the description proceeds, the invention consists in the novel construction, combination and arrangement of parts, all as will be described more fully hereinafter, illustrated in the drawings, and particularly pointed out in the claims.

In the drawings:

Fig. 1 is a cross sectional view through a conventional railway track and illustrating in end view a ballast remover constructed in accordance with the invention.

Fig. 2 is a top plan view of the ballast remover, and

Fig. 3 is a side elevation of the track and illustrating, also in side elevation, the ballast remover of my invention.

The invention consists generally in a light portable carriage adapted for movement along and upon the rails of a railroad track and having mounted thereon power-operated mechanism for clearing away or throwing aside the ballast between ties of the railroad track. The ballast clearer as a unit is of comparatively light weight so that it may be applied to and removed from the tracks of the road-bed easily and with little difficulty. The clearer is featured by simple means for advancing the clearer mechanism as well as for determining the depth of operation of such mechanism upon the ballast, and also involves a structure whereby the clearer mecha-

2

nism may be revolved or rotated upon the supporting carriage so as to operate in either direction laterally of the trackway.

More particularly, the supporting vehicle includes a body 4 of light construction yet possessing sufficient strength to support the clearer mechanism without danger of breakage. This carriage may consist of a rectangular frame formed of angle or channel bars as shown, properly reinforced by cross members or braces to insure rigidity. The vehicle is equipped with laterally disposed axles 5 upon the ends of which are secured flanged wheels 6 to engage and travel upon the rails 7 of the track.

Mounted upon the vehicle frame 4 and for horizontal rotation thereon is a skeleton platform represented generally at 8. This platform may consist of relatively light angle or channel bars secured together in rigid relationship by strut members or braces, and including a central channel member 9 pivoted as at 10 centrally of the vehicle frame 4. The platform in the present instance is of substantially equal length with the vehicle frame 4 and may be slightly wider than the said frame, and includes end bars, in the form of channel members, 11. These bars are parallel with one another and are disposed laterally of the vehicle frame and constitute spaced rails of a trackway, the purpose of which will be described more fully hereinafter.

Superimposed upon the skeleton platform and supported thereby is a carriage represented generally at 12. This carriage includes spaced parallel bars 12' disposed longitudinally of the skeleton platform, which bars have mounted thereon rollers or wheels 13 to travel upon the members 11 of the skeleton frame trackway. The bars 12' project at one end beyond the skeleton platform 8 and rigidly secured to the projecting ends of said bars and extending laterally therefrom is a ballast clearer frame 14. This frame includes spaced parallel bars 14' at the extreme ends of which and depending therefrom is a ballast clearer wheel or drum 15 mounted for rotation upon a shaft 16 adjustably supported in the depending arms 17 constituting a part of the ballast clearer frame. Mounted also upon the bars 14 and disposed laterally thereof is an axle or shaft 18, secured to the ends of which are drive wheels or pulleys 19. The shaft 18 also carries a sprocket or sheave 21, over which passes a chain or clearer band 22 having ballast clearer cleats 23 arranged thereon in spaced relation; the band or sprocket 22 passing over the drum 15. The power wheels or pulleys 19 are driven by

belts 24 extending inwardly of the frame and passing around drive pulleys 25 secured to a shaft 26 supported by and parallel with the bars 12' of the carriage frame. A power source 27, such as an internal combustion engine or other type of motor, is supported also upon the bars 12' of the carriage frame, which motor drives the shaft 26. This shaft is equipped with a conventional clutch 28 operated by the hand lever 29 in order that the power connection between the motor 27 and the clearer mechanism may be made or broken as desired or required.

The clearer frame is equipped with means whereby the clearer mechanism at the end thereof may be raised or lowered in carrying out the ballast removing operation. The means for bringing about and accurately governing this raising or lowering movement includes a supplementary roller frame 30 comprising spaced parallel arms as shown in Fig. 2 straddling the adjacent rail or bar 11 constituting a track element of the carriage. The inner ends of the arms 30 are pivoted as at 31 to the carriage frame structure, while a roller or wheel 32 is rotatably mounted at the free ends of these arms and rests upon the track element 11 of the carriage. Pivoted between the arms 30 and above the horizontal plane of the pivot 31 and roller 32 is a trunnion block 33, through which extends a threaded shaft 34 mounted at its opposite end in a suitable bearing 35 on the carriage frame and equipped at its inner end with a hand-operated control wheel 36. From this construction it is obvious that rotation of the hand wheel 36 causes the shaft 34 to rotate in the internally threaded trunnion block 33 to cause the clearer frame to move up or down depending upon the direction of rotation of the hand wheel.

The means for moving the carriage upon the trackway 11 includes a pair of sprocket chains 37, one disposed at each end of the carriage frame. These chains are secured at their ends as at 38 to the extremities of the rails 11 of the carriage trackway. The carriage at each end rotatably supports a pair of sprockets 39, the teeth of which are engaged with the links of the sprocket chain 37. From these sprockets the chain lengths project upwardly and pass over a sprocket 40 also carried by the carriage frame above the horizontal plane of the sprockets 39. The shaft 41 which supports the sprocket 40 has secured thereto a larger sprocket wheel 42 over which passes a chain 43 in turn passing over a smaller sprocket 44 secured upon shaft 45. The shaft 45 has secured to one end thereof an operating wheel 46. It is obvious, therefore, that rotation of the hand-operated wheel 46 will cause the larger sprocket 42 to rotate, carrying with it sprocket 40 over which passes the feed chain 37. Inasmuch as the ends of this chain are permanently secured to ends of the rails 11 of the carriage trackway, the entire clearer frame will be caused to move along the trackway 11 in a direction governed by the direction of rotation of the hand wheel 46. This particular chain and sprocket arrangement also assists in maintaining the traveling carriage securely upon its trackway.

In operation, the vehicle is placed upon the rails of the trackway to be operated upon, and is positioned so that the clearer wheel will be disposed above the ballast to be removed between ties. The clearer frame is moved inwardly of the vehicle preferably to the limit of its travel on the trackway 11, whereupon the depth determining hand wheel is rotated to accurately place the wheel 15 of the clearer mechanism. The motor

is started and the clutch operated so as to impart power to the clearer mechanism. Through the belt and sprocket arrangement described, the clearer wheel with its cleats 23 will rotate in a counterclockwise direction, causing the ballast to be thrown beyond the road-bed. The operator of the machine determines the depth to which the clearer wheel will be dropped in this operation, and will also operate the hand wheel 46 to cause the entire carriage to advance laterally of the road-bed. As the clearer wheel approaches the adjacent rail 7, the carriage frame is operated to lift the clearer wheel so as to clear the said rail, whereupon it is dropped so as to operate upon and remove the ballast from the rail to the ends of the ties. When all ballast has been cleared in this manner, the platform may be rotated upon the vehicle so as to position the clearer mechanism reversely, and when the clearer wheel has been properly positioned between the desired ties, it is lowered and the operation proceeds to clear away the ballast from the opposite side of the road-bed.

It may be found desirable where a considerable length of trackway is to be treated preparatory to tie replacement, to maintain the clearer mechanism so as to operate upon one side of the trackway between successive pairs of ties throughout the length of trackway to be treated, after which the platform is rotated through 180 degrees so as to operate upon the ballast at the opposite side of the road-bed, as will be understood. It may also be found desirable to maintain the track clearer mechanism to operate without revolving the platform. This may be done by bodily lifting the car with its supporting mechanism and reversing its position upon the road-bed. It is desired that the proportions of the clearing mechanism and the supporting frame therefor be such that when the clearer frame is retracted, that is moved to its limit inwardly of the trackway, the clearer wheel will be disposed substantially midway between the rails of the road-bed. In this way, the clearer wheel will be insured of reaching all ballast between rails, and what little ballast remains directly beneath and in the vicinity of the rail 7 may be easily cleared away by hand.

From the foregoing it is obvious that I have constructed a ballast clearer mechanism fully capable of accomplishing the various objects sought, which involves relatively few simple and readily assembled parts, which has its parts so constructed and arranged as to minimize the opportunity for wear, breakage or derangement, which does not require the exercise of extraordinary skill or ability in its proper operation, which minimizes manual labor in ballast clearing operations, and which will prove highly practical and efficient in use.

I claim:

1. In a ballast remover, a vehicle, a trackway on said vehicle, a carriage movable on said trackway, a clearer frame secured to and projecting laterally from said carriage, a roller resting upon said trackway and supporting said carriage, and means for rocking said carriage and the clearer frame on said roller.

2. In a ballast remover, a vehicle, a trackway on said vehicle, a carriage movable on said trackway, a clearer frame secured to and projecting laterally from said carriage, a roller resting upon said trackway and supporting said carriage, means for rocking said carriage and clearer frame on said roller, clearer mechanism carried

by said frame, and means for operating said mechanism.

3. In a ballast remover, a vehicle, a trackway on said vehicle, a carriage, a clearer frame secured to said carriage and projecting laterally therefrom, a roller supporting one end of said carriage, a second roller mounted on plates pivotally connected to said carriage supporting said clearer frame and spaced from said first named roller, both of said rollers resting upon said trackway, and means on said carriage for rocking the latter upon its supporting roller.

4. In a ballast remover, a vehicle, a trackway on said vehicle, a carriage, a clearer frame secured to said carriage and projecting laterally therefrom, a roller supporting said carriage and resting upon said trackway, a plate pivoted at one end to said carriage and having its opposite

end disposed beneath said frame, a roller carried by said plate and resting upon said trackway, a trunnion block carried by said plate, a screw shaft anchored in said carriage and threadedly engaged in said trunnion block, and clearer mechanism carried by said frame.

ROYCE KERSHAW.
